UNITED STATES PATENT OFFICE.

SAM GWYN SCANLAN, OF CHICAGO, ILLINOIS.

HEATER.

SPECIFICATION forming part of Letters Patent No. 743,571, dated November 10, 1903.

Application filed July 6, 1903. Serial No. 164,438. (No model.)

To all whom it may concern:

Be it known that I, SAM GWYN SCANLAN, a citizen of the United States, residing in the city of Chicago, County of Cook, and State of Illinois, have invented a new and useful Improvement in Heaters, of which the following is a specification.

My invention relates to heaters adapted for the use of surgeons, physicians, and others requiring steam or heated water, sterilized or unsterilized, or compressed air for surgical, therapeutic, or domestic purposes.

The object of my invention is to provide a convenient, simply-constructed, and readily-operable means for supplying at will these various requirements, and I attain my object by the mechanism illustrated in the accompanying drawings, in which—

Figure 1 is a general side view of the complete device. Fig. 2 is a view of the tank and connections, taken chiefly in vertical longitudinal section.

In connection with my present invention attention is directed to an application for patent on a heater constructed on somewhat similar lines, for which I filed an application for patent in the United States Patent Office April 15, 1903; Serial No. 152,749.

Similar letters of reference denote similar parts in both figures of the drawings.

a represents a tank or other vessel, which is preferably held in an upright position by means of a stand *b*. This stand may be of any suitable design, but is preferably so constructed that said tank is removable therefrom. With exception of certain apertures, hereinafter described, said tank *a* is air and liquid tight, and at a convenient point, preferably in the top thereof, is the nipple or other pipe-coupling *c*, through which air or other gas may be introduced in said tank under pressure. The compressed gas may be supplied to said tank in any suitable manner—for example, by means of the pump *d*, which connects with said nipple *c* through the hose *d'*.

In order to remove impurities from the air as it is being introduced into the tank, it is desirable that a filter *e* should be provided in said hose *d'*. *e'* represents a shut-off valve in the hose *d* for preventing the escape of air

from the tank. A filler-cap *e*, which is preferably screw-threaded, is provided in the upper portion of the tank to afford means for introducing the water.

At or near the top of the tank is a coupling *f*, which forms a point of connection for the hose *f'*. This hose may be furnished with any suitable shut-off valve and is designed to be used in connection with sprays, atomizers, and similar contrivances used by physicians and others. Although not a necessary part of my invention, it is desirable to provide a framework *g* at the top of the tank to hold the receptacles *g' g'*. Said frame *g* is suitably supported by means of a column *h*, mounted upon the top of the tank.

i represents a discharge-pipe which has a receiving-opening *i'* inside of the tank *a*, near the bottom thereof, and has a discharge-opening *i''* at any convenient point. The valve or faucet *i''* is provided in said pipe *i* to control the discharge of water through the same. Although I prefer that the pipe *i* shall pass upward through the interior of the tank *a*, said pipe may extend upward along the outside thereof, it being not essential that any considerable portion of said pipe, except the receiving-opening thereof, shall lie within said tank. An air or water tight wall or diaphragm *j* is located in the lower portion of the tank, so as to form therein two chambers *a'* and *a''*. By preference the upper chamber *a'* is much larger in capacity than said lower chamber *a''*.

On the side of the tank at a slight distance above the diaphragm *j* is the valve-casing *k*, which is provided with three apertures *k' k'' k'''*. Said aperture *k'* connects with the upwardly-extending pipe *j'*. Said aperture *k''* connects directly with the interior of the tank above the diaphragm *j*, and said aperture *k'''* connects with the pipe *m*, which connects with the chamber *a''* immediately below the diaphragm *j*.

The valve *n* is so constructed as to constitute in conjunction with the casing *k* a three-way cock, said valve having the straight central duct *n'*, extending completely through said valve, and the side duct *n''*, leading laterally from said duct *n'*. The parts are so arranged that when valve *n* is in one rotated position the pipe *m* is in communication with

the tank a only and when said valve is in a second rotated position pipe m is in communication with pipe j' only.

A second valve - casing o is located at or 5 near the top of the tank and in conjunction with its valve p constitutes a three-way cock similar in construction and operation to the valve - casing k and valve n therein. Said casing connects with the pipe j' , tank a , and 10 pipe q in such a manner that when the valve p is in one rotated position the pipe j' is in communication with the tank only and when 15 said valve is in the second rotated position the valve j' is in communication with the pipe q only. This last condition is illustrated in Fig. 2 of the drawings. Said pipe q leads to any suitable device—such, for example, as an atomizer or a sterilizer. In order to control the escape of fluid through said pipe q , a shut- 20 off valve q' is provided therein.

Beneath the tank a is arranged a heating-coil r , comprised of a number of turns of pipe, one extremity, r' , communicating with the chamber a^2 and the other extremity, r^2 , 25 communicating with the bottom of the chamber a' . A shut-off valve r^3 is provided, preferably, in the riser-pipe r^4 and leads to the heating-coil r .

The burner s of any suitable design is ar- 30 ranged below the heating-coil r in such manner that the heat from said burner shall strike said coil and quickly raise the temperature of the water therein. In operation water in its natural state—that is to say, cold 35 and unsterilized—is introduced into the chamber a' through the filler-cap e^2 in such quantity as to leave an air-space at the top of the tank. After the filler-cap has been replaced, so as to render the tank air-tight, air or other 40 gas is introduced under pressure into the top of chamber a' by means of the air-pump d or other suitable means.

The function of the compressed air or other 45 gases at the top of the tank a' is to afford sufficient pressure to enable water to be drawn off through the discharge-pipe i or pipe q . By proper manipulation and use of the apparatus the latter is now in readiness to furnish air or water under a variety of conditions, which will now separately be described.

First. Cold air under pressure may be drawn off directly from the chamber a' through the valve-casing o and pipe q .

Second. Cold unsterilized water may be 55 drawn off directly from the chamber a' by rotating the valve p so that there will be a connection between the pipes j' and q and rotating the valve n so that there will be a connection between the chamber a' and the 60 pipe j' .

Third. If hot water is wanted for immediate use, the burner s may be lighted and the valve r^3 opened to such an extent that water may pass slowly through the heating-coil r 65 into the chamber a^2 . On account of the length of coil by supplying a sufficient amount of

heat the water may be raised to boiling temperature as it passes through said heating-coil. As soon as sufficient water has been thus introduced into the chamber a^2 the 70 heated water may be drawn off through the discharge-pipe i by opening the valve i^3 therein. During this time, of course, the valve n will be rotated to such a position as to shut off communication between the chamber a' 75 and pipe m to prevent the water from said chamber a' from passing to said chamber a^2 by way of said pipe m instead of through the heating-coil r .

Fourth. If steam is wanted, it may be obtained by first causing the generation of steam in the chamber a^2 by means of the burner s and heating-coil r and then drawing off the resulting steam through the valves n and p 80 and pipe q .

It is obvious that in case it is desired to sterilize all the water in the tank this may be accomplished by lighting the burner, opening the valve r^3 , and rotating the valve n to such a position that the pipe m will be in communication with the chamber a' . Under 90 these conditions the chamber a^2 will become completely filled with water and there will be a complete circuit between the chambers a' and a^2 through the pipe r^4 , coil r , and pipe m . In order to completely sterilize all of the water, it will be necessary merely to continue the heating of the water for a sufficient period of time. In using the apparatus under 95 the last-named conditions the entire amount 100 of water for sterilization may be drawn off at will through the discharge-pipe i .

It is desirable when steam is being drawn off from the top of the chamber a' through the pipes m , j' , and q that the valve r^3 remain closed or partially closed to prevent water from the chamber a' from passing into the chamber a^2 , and thereby completely filling the latter. Moreover, if the valve r^2 is closed and valves n and p out of communication with chamber a' steam may be generated in the chamber a^2 , so that a steam-pressure in the chamber a^2 may be obtained greater than the pressure in the chamber a' . Furthermore, under these last-named conditions by shutting off communication between chambers a' and a^2 it would be possible at 110 any given time to draw off either steam from the upper portion of chamber a^2 , boiling water through the discharge-pipe i from the lower portion of chamber a^2 , cold air from the upper portion of chamber a' , or comparatively cold water from the lower portion of chamber a' .

I do not wish to be understood as limiting myself to any particular form of tank or methods of supporting same or of introducing compressed air thereinto. These elements are non-essential and for that reason are not specifically described in the appended claims.

What I do claim as new, and desire to secure by Letters Patent, is—

1. In a heater, the combination of a tank having two chambers therein arranged one above the other, a heating-coil connected to the lower chamber and also to the lower portion of the upper chamber in said tank; a discharge-pipe leading from the lower portion of said lower chamber and a second discharge-pipe leading from the upper portion of said lower chamber. 5

10. 2. In a heater, the combination of a tank having two chambers therein arranged one above the other, a heating-coil connected to the lower chamber and also to the lower portion of the upper chamber, a discharge-pipe leading from the lower portion of said lower chamber, a second discharge-pipe leading from the upper portion of said lower chamber, and a three-way cock in said second discharge-pipe adapted to discharge the heated fluid directly from said lower chamber, to return the heated fluid from said lower chamber to said upper chamber, or to discharge directly the fluid of said upper chamber. 15

20. 3. In a heater, the combination of a tank having two chambers therein one above the other, a heating-coil connected to the lower chamber and also to the lower portion of the upper chamber in said tank, a discharge-pipe leading from the lower portion of said lower chamber, a second discharge-pipe leading from the upper portion of said lower chamber, a three-way cock in said second discharge-pipe connecting with the lower portion of said upper chamber, said three-way cock being adapted to discharge fluid directly from said lower chamber, to return the fluid from said lower chamber to said upper chamber, or discharge directly the fluid of said upper chamber; and a second three-way cock in said second discharge-pipe connecting with the upper portion of said upper chamber, said second three-way cock being adapted to discharge the fluid directly from said lower chamber, to return the fluid from said lower chamber to said upper chamber, or to discharge directly the fluid from the portion of said upper chamber above said first cock. 25

30. 4. In a heater, the combination of a tank having two chambers therein arranged one above the other, a heating-coil connected to the lower chamber and also to the lower portion of the upper chamber in said tank; a discharge-pipe leading from the upper portion of said lower chamber and a three-way cock in said discharge-pipe connecting with said upper chamber, said cock being adapted to discharge the fluid directly from said lower chamber, to return the heated water from said lower chamber to said upper chamber, or to discharge directly the fluid from said upper chamber. 35

40. 5. In a heater, the combination of a tank having two chambers therein arranged one above the other, a heating-coil connected to the lower chamber and also to the lower portion of the upper chamber in said tank; a discharge-pipe leading from the upper portion of said lower chamber, a three-way cock in said discharge-pipe connecting with said upper chamber at a point above said first three-way cock, said second cock being adapted to discharge directly the fluid from said lower chamber, to return the fluid from said lower chamber to said upper chamber, or to discharge directly the fluid from the portion of said upper chamber above said first cock. 45
